(57) CLAIM

The ornamental design for a ceiling fan as shown and described.

DESCRIPTION

FIG. 1 is a top perspective view of a ceiling fan, showing my new design.

FIG. 2 is a bottom perspective view of the ceiling fan.

FIG. 3 is a top view of the ceiling fan.

FIG. 4 is a bottom view of the ceiling fan.

FIG. 5 is a front view of the ceiling fan.

FIG. 6 is a rear view of the ceiling fan.

FIG. 7 is a right-side view of the ceiling fan; and,

FIG. 8 is a left-side view of the ceiling fan.

Dash-dash broken lines illustrate portions of the ceiling fan that form no part of the claimed design. The appearance of any portion of the ceiling fan between the symbolic dash-dot break lines forms no part of the claimed design.

1 Claim, 8 Drawing Sheets
